UNITED STATES PATENT OFFICE

CHARLES E. LUCKE, OF NEW YORK, N. Y., ASSIGNOR TO WORTHINGTON PUMP AND MACHINERY CORPORATION, OF NEW YORK, N. Y., A CORPORATION OF VIRGINIA

STEAM CONDENSER

Application filed August 3, 1925. Serial No. 47,672.

This invention relates to steam condensers of the surface type, the object being to provide an improved casing construction for such condensers which shall be cheaper, lighter and stronger than those heretofore used.

In accordance with this invention, the condenser casing is built up of steel beams or shapes of suitable form, according to the form of condenser shell desired, and upon these beams is supported a light shell to enclose the condensing space, this shell being supported by the beams at such intervals and in such manner as to enable comparatively thin rolled sheet metal or other suitable material to be used. I am thus enabled to make a very light, strong and cheap condenser casing, and to avoid the internal cross bracing and interference with tube arrangement usual in large condensers.

For a full understanding of the invention, there is shown in the accompanying drawings forms of condenser casings embodying the invention in preferred forms, and these constructions will now be described in detail and the features forming the invention then be specifically pointed out in the claims.

In the drawings—

Figure 1 is a diagrammatic cross-section of a condenser shell of the common cylindrical form embodying the invention;

Figure 2 is a central longitudinal section of the same;

Figure 3 is a view similar to Fig. 1, showing a modification with the beams on the outer side of the casing;

Figure 4 is a side view of Figure 3, and

Figures 5 and 6 are views similar to Fig. 1, showing the invention applied to condensers of other forms.

Referring now especially to Figs. 1 and 2, A is the exhaust inlet and B the condenser shell, which preferably is of rolled sheet metal but may be of cast metal or any other suitable material, supported by a series of beams C, shown as of standard T-form in cross-section and as extending entirely about the inner side of the condenser B across the exhaust inlet A, a very strong form of construction being secured by these circular or ring beams.

These beams are sufficient in number and so

spaced that a comparatively light shell may be used. It is found in practice that these beams do not substantially interfere with the free passage of the exhaust from the exhaust inlet A to the condensing surfaces, even though placed at the closest intervals necessary in practice. The condensing tubes 10 are shown in dotted lines as arranged in shallow belts and in convolutions for steam distribution, and the usual hot-well 11 at the bottom of the condenser is shown, the central beam C passing across the top of this hot-well.

In Figs. 3 and 4 a construction similar to Fig. 1 is shown, except that the beams D are applied on the outer side of the shell B, preferably extending upward on the exhaust connection A, as shown, and the shell is also supported at the exhaust connection by beams E extending across the exhaust opening.

In Fig. 5 an octagonal shaped condenser shell F is shown, and the beams are in the form of bracing frames G of triangular form, each extending over two sides of the octagon so as to form a rectangular condensing space between them.

In Fig. 6 a condenser casing of the bowl or half cylinder form is shown, with beams I of any suitable cross-section extending over the outer side of the casing H, the exhaust opening extending the entire width of the casing and having supporting beams crossing the exhaust opening or not, as desired.

It will be understood that the invention is not to be limited to the form or arrangement of parts illustrated, as constructions embodying the invention will be varied widely according to the form of condenser desired, while retaining the invention defined by the claims.

What is claimed is:

1. A steam condenser having a shell formed of plate material and supported by metal shapes arranged outside the condensing space of the condenser and spaced to support the shell against the condenser stresses without internal cross-bracing in the condensing space.

2. A steam surface condenser having a shell formed of plate material and supported by metal shapes outside the condensing space

of the condenser and crossing the exhaust opening and spaced to support the shell against the condenser stresses without internal cross-bracing in the condensing space.

5 3. A steam surface condenser of circular form having a shell formed of plate material and supported by circular beams extending around the condensing space and across the exhaust opening and spaced to support the shell against the condenser stresses without internal cross-bracing in the condensing space.

10 4. In a steam condenser, a shell having an exhaust opening and formed of plate material and supported by metal shapes conforming to the shape of the shell and crossing the exhaust opening, said metal shapes spaced to support the shell against condenser stresses without internal cross-bracing in the condenser.

15 5. In a steam condenser, a shell having an exhaust opening and formed of plate material, metal shapes within said shell and conforming to the shape of the shell and crossing the exhaust opening and lying wholly without the condenser space in the condenser, said metal shapes spaced to support the shell against condenser stresses without internal cross-bracing in the condenser.

20 In testimony whereof, I have hereunto set my hand.

CHARLES E. LUCKE.
